UNITED STATES PATENT OFFICE.

CYRUS W. SALADEE, OF PADUCAH, KENTUCKY.

IMPROVEMENT IN STIRRUPS.

Specification forming part of Letters Patent No. 42,512, dated April 26, 1864.

CASE B.

To all whom it may concern:

Be it known that I, CYRUS W. SALADEE, of Paducah, in the State of Kentucky, have invented certain new and useful Improvements in Stirrups for Riding-Saddles; and I do hereby declare that the following is a full and exact description thereof, reference being had to the accompanying drawings, and to the letters of reference thereon marked.

In the drawings, Figure 1 is a side elevation. Fig. 2 is a front elevation, and Fig. 3 is a plan view of the foot-bar (or bottom) of the stirrup and the manner of attaching the guard.

To enable others to make and use my invention, I will fully describe it.

This invention relates to a new article of manufacture, and it consists in a guard to prevent the foot from passing too far through the stirrup, formed or stamped out of a rod or plate of metal, and to be secured at one end to the stirrup foot-bar, as herein set forth.

This guard is to be attached to any metallic stirrup of the usual form, as shown at A.

B is the guard, formed by looping a rod, as shown at Fig. 2, and then bending the looped rod so as to form a semicircular guard, as shown in Figs. 1 and 3, of a form substantially as shown in the drawings. The ends of the rod forming the loop are flattened out and secured by screws or rivets to the under side of the stirrup foot bar, as shown in Fig. 3.

This guard is to be manufactured in various styles, and is to be sold in pairs by the stores usually selling horse furniture, so that one can buy a pair of them and have them attached to his old stirrups by the "village blacksmith."

What I claim as new, and desire to secure by Letters Patent as a new article of manufacture, is—

The guard B, constructed, operating, and attached substantially as set forth.

CYRUS W. SALADEE.
